Inventor,
HANS JADE
By Victor J. Evans
Attorney.

UNITED STATES PATENT OFFICE.

HANS JADE, OF SAN FRANCISCO, CALIFORNIA.

BASCULE TOY BRIDGE.

Application filed September 29, 1926. Serial No. 138,466.

This invention relates to improvements in toy bridges, and has particular reference to a mechanical toy bridge.

The principal object of this invention is to produce a toy bridge for use in connection with toy trains or the like toys whereby the action of a bascule bridge may be simulated.

Another object of this invention is to produce a toy of this character which is simple in construction, and therefore cheap to manufacture.

A further object is to produce a toy which is neat in appearance and one which will make a pleasing combination with the standard toy railroad equipment now upon the market.

Other objects and advantages will be apparent during the course of the following description.

20 In the accompanying drawings forming a part of this specification, and in which like numerals are employed to designate like parts throughout the same,

Figure 1 is a side elevation of my improved 25 toy bridge showing the same in closed position,

Figure 2 is a view similar to Figure 1, showing the bridge in open position,

Figure 3 is a fragmentary detail view 30 showing one of the gates in open position,

Figure 4 is a fragmentary detail view showing the manner of operating one of the gates,

Figure 5 is a top plan view of Figure 1,

Figure 6 is a top plan view of the operating mechanism,

Figure 7 is a vertical cross-section taken on the line 7—7 of Figure 6,

Figure 8 is a vertical cross-section taken 40 on the line 8—8 of Figure 6,

Figure 9 is a vertical cross-section taken on the line 9—9 of Figure 6, and

Figure 10 is a detail perspective view showing the gate operating mechanism.

45 In the accompanying drawings wherein for the purpose of illustration is shown a preferred embodiment of my invention, the numeral 5 designates a framework representing the bed and sides of a stream or other similar channel. This frame 5 has abutments 6 and 7 between which the bridge 8 is swung.

The bridge portion is pivoted as at 9 to the frame 5 at a point adjacent the abutment 6. Positioned within the abutment 6 is a clock mechanism 11 having a spring 12

adapted to be tensioned by a suitable key which is placed over the winding shaft 13. This spring 12 transmits motion to a shaft 14 having a counter-weight 16 thereon. 60 This shaft also carries a disc 17 having notches 18 formed therein and diametrically opposite each other. To the disc 17 is secured a link 19 which is in turn pivoted to the bridge 8, as shown at 21.

65 A similar link 22 is connected to the opposite side of the bridge and to a disc 23, also mounted upon the shaft 14. The disc 17 has a latch 24 pivoted adjacent thereto, which latch has a dog 26 adapted to enter 70 one of the notches 18 in the disc.

A starting lever 27 is adapted to engage the latch lever 24 for the purpose of pulling the dog out of the notch 18 when it is desired to start the clock mechanism. 75

The disc 22 has formed thereon projections 29 and 31 which projections are adapted to alternately engage levers 32 and 33, respectively. The levers 32 and 33 are positioned upon a shaft 28 carried upon 80 the side of the abutment 6. A rod 34 positioned parallel to the shaft 28 extends through the frame 5 and into the abutment 7 (see Figure 2).

This shaft is provided with cranks 36 85 which in turn extend upwardly. The links 37 terminate in a pointed end, engaging one end of a gate 38 pivoted as at 39.

It is of course understood that there is one of these gates at each end of the bridge. 90

The shaft 34 is rocked through a link 41 extending from the lever 42 carried upon the shaft 28 through the lever 36.

The result of this construction is that after the toy bridge has been placed in an operative position and the spring 12 tensioned, movement of the lever 27 will cause the dog 26 on the latch 24 to be withdrawn from the notch 18 in which it is resting. The spring now serves to give a half revolution to the 95 shaft 14. Immediately upon the initial movement of the shaft 14, the disc 23 will have one of its projections, as for instance the projection 31, engage the under surface of the lever 33 which will rock the shaft 28 and the rod 34 in the same direction. This 100 will push up on the links 37 thus causing the gates 38 to move to the dotted line position of Figure 3.

As soon as the shaft 14 has made a half 110 revolution, the dog 26 will again drop into one of the slots 18 and arrest further motion.

This will leave the bridge in an open position as set forth in Figure 2.

By again operating the lever 27 and raising the dog 26, the next half revolution as above described will cause the bridge to return to its closed position, as shown in Figure 1.

Just previous to the bridge arriving at its closed position, the projection 24 and the disc 23 will engage the upper surface of the lever 32 and move the shaft 28 and rod 34 in such a direction that the links 37 will cause the gates 38 to move to an open position.

It will thus be seen that I have produced a very simple toy bridge wherein the mere winding of a spring and the actuation of a single lever will cause both the bridge to open and close, and also the gates to be automatically operated.

It is to be understood that the form of my invention herewith shown and described, is to be taken as a preferred example of the same, and that various changes relative to the material, size, shape and arrangement of parts may be resorted to without departing from the spirit of the invention or the scope of the subjoined claim.

Having thus described my invention, I claim:

In a toy of the character described a pair of portable spaced abutments connected one to the other, a bridge portion pivoted to one of said abutments and adapted to move into contact with the other of said abutments, a gear train positioned within one of said abutments, said gear train having a shaft, a plurality of discs carried on said shaft, one of said discs having notches in the periphery thereof, a latch adapted to engage said notches for the purpose of retaining said disc against rotation, the other of said discs having projections thereon, a shaft extending between said abutments, gates positioned on said abutments, means for actuating said gates from said last mentioned shaft, means for rocking said last mentioned shaft through a lever engaging said projections formed on said disc and link connections extending between said first mentioned disc and said bridge portion for the purpose of actuating said bridge portion.

In testimony whereof I affix my signature.

HANS JADE.
